UNITED STATES PATENT OFFICE.

GEORG VOGT, OF LAHR, GERMANY.

PERMUTATION-LOCK.

SPECIFICATION forming part of Letters Patent No. 509,006, dated November 21, 1893.

Application filed April 15, 1893. Serial No. 470,487. (No model.)

To all whom it may concern:

Be it known that I, GEORG VOGT, railway manager, of Lahr Railway Station, Baden, in the Empire of Germany, have invented a new and useful Permutation Lock, of which the following is a specification, reference being had therein to the accompanying drawings.

The object of the present invention is to form a safety-lock which lock is of the class known as combination or letter-locks and which offers still greater difficulties than heretofore to unauthorized persons in unlocking it, as not only the usual word or number is required to be known but also an extra secret device has to be operated.

In the accompanying drawings the interior mechanism of the lock is clearly illustrated.

Figure 1 is a vertical section through the center line of the lock. Fig. 2 is a similar section showing the parts in the position they would occupy when the lock is unlocked. Fig. 3, is a top view of the number disks. Fig. 4 is a top view of the coupling disks. Fig. 5 shows the middle plate. Fig. 6 shows the bed plate. Fig. 7 is a side view of the lower coupling part. Fig. 8, shows in vertical section the mechanism for securing the lock in its open position and in a state of rest, and Fig. 9 is a vertical section of the same mechanism in action.

The essential features of the new safety lock for which the present application is made consist in three main parts, a bed-plate, A, a middle plate B for setting the letter disks and a cover plate C for the reception of the letter disks. The last named plate C carries, as shown in the drawings, four shanks *a* with button-heads *b* and the letter or numbered disks *c* in suitable recesses. The plate itself is provided with marks *d*, Fig. 3, for setting the numbers or letters required for unlocking the lock. Each shank *a* carries at its lower extremity below the plate C, a toothed disk *e*. The middle plate B Fig. 5 is provided with four recesses *f* corresponding to the said toothed disks *e* into which recesses are fixed the disks *g* shown in Fig. 7. The latter carry shanks *h*, whose upper ends are made to fit into corresponding holes *i* of the shanks *a*. These holes *i* also receive the spiral springs *k* which press against the ends of the shanks *h*. Pins *l* are inserted into the shanks *h*, in a position therein

below the plate B, so as to keep the disks *g* in their proper place. The lower extremity of each shank *h* is provided with a bit or web *m* (see Fig. 7), which fits and passes through a corresponding opening *n* formed in the bed plate A, see Fig. 6. Each of the disks *g* has a pin *o* which is made to enter into the toothed disk *e* in order to couple the two shanks *a* and *h* together. In addition to the recesses for the disks *g*, another recess and hole near one end of the plate B are provided for the reception of the locking spring catch *p*, which latter is retained in its position by a spring *q*. The spring catch *p* enters into a suitable notch of the locking bolt *r*, which latter passes into the interior of the lock through an opening at the end thereof. A screw *t*, passing through these plates B and C and having screw threads *s* and a square part *u* guided in a correspondingly formed square hole in the bed plate A, is provided to facilitate the lifting away of the upper plates A and C from the bed plate A when the correct position of the letter disks has been attained, and thus, by retiring the locking spring catch *p* from its notch in the shooting bolt *r*, the lock is unlocked. Screws *z* are passed through the plate A for the purpose of regulating the lift of the plates B and C. The screw *t* serves also, after having lifted the plates B and C away from the plate A, to separate the plates B and C from each other by giving it several turns, which is now possible, as after having lifted the plates B and C up, the square part *u* of the screw *t* is retired from the square opening *v* in the fixed plate *v* and enters into the larger hole *w* in the bed plate A. By separating the plates B and C from each other, the pins *o* of the disks *g* are brought out of contact with the toothed disks *e*, so as to allow of altering the numbered disks to another letter or number. To prevent the plates B and C from approaching the plate A by accident during the operation, the upper plate C is provided on its inner side with a bell crank lever *x* which is lodged in a recess in the plate B, Fig. 9, and is kept in its normal position by a spring *y*, so that the free arm of it is made to enter the hole *j* in the plate A, but, by twisting the screw, will bear on the plate A.

The action of the mechanism for unlocking is as follows: After having turned the num-

bered disks by means of the button heads *b* so as to place the required numbers opposite the marks *d*, the shanks *h* are, through the medium of the coupling up of the toothed disks *e* with the disks *g* and their pins *o*, turned so that their bits or webs *m* coincide correctly with the slot *n*, Fig. 6. By now pulling the screw *t*, all the bits or webs *m* will pass through the slots *n* and at the same time the catch *p* will be lifted out of the notch in the shooting bolt *r*, which latter can then be retired and the lock be opened.

What I claim, and desire to secure by Letters Patent of the United States, is—

- 15 1. In a permutation lock a base plate having an opening to receive a notched bolt, an upper plate movable toward and from said base plate and carrying a catch for engaging the notched bolt, a series of rotating indicating disks connected with means for holding said plates in proximity, and means for separating said plates to release the bolt when the disks are properly set, substantially as described.
- 20 2. In a permutation lock, a base plate having a series of openings through the same with grooves in the sides of said openings, a plate above the same movable vertically thereof, a series of indicating disks, shanks connected

to said disks extending through the openings *g* and having projections adapted to register with the grooves, a notched bolt, a catch carried by the upper plate for engaging said bolt, and means for separating the plates when the projections are placed in alignment with the grooves, substantially as described.

3. In a permutation lock a base plate having a series of grooved openings, a vertically movable middle plate having a series of recesses, disks seated in said recesses having shanks depending through the openings in the base plate, projections carried by the shanks adapted to align with the grooves, a vertically movable cap plate, a series of shanks extending through openings therein, disks on their lower ends detachably engaging the disks of the middle plate, indicator disks mounted on the shanks above the upper plate and means whereby the middle and cap plates may be elevated and also the cap and middle plates separated, substantially as described.

In witness whereof I hereunto set my hand in presence of two witnesses.

GEORG VOGT.
